United States Patent Office

Des. 205,585
Patented August 23, 1966

205,585

DEVICE FOR GROOMING DOGS AND CATS

Ada Evelina Danielson, 1315 E. Main, Riverton, Wyo.

Filed May 20, 1965, Ser. No. 85,487

Term of patent 14 years

(Cl. D12—2)

Fig. 1

Fig. 2

Fig. 3

FIG. 1 is a top perspective view of a device for grooming dogs and cats, showing my new design.

FIG. 2 is a side elevational view thereof.

FIG. 3 is an elevational view showing the side opposite to the side shown in FIG. 2.

I claim:

The ornamental design for a device for grooming dogs and cats, as shown.
